Primary Examiner — Mary Ann Calabrese*Assistant Examiner* — Katelin G Kloberg(74) Attorney, Agent, or Firm — K&L Gates LLP(57) CLAIM

The ornamental design for a bed frame as shown and described herein.

DESCRIPTION

FIG. 1 is a top perspective view of a bed frame showing the new design:

FIG. 2 is a top view thereof;

FIG. 3 is a side view thereof; and,

FIG. 4 is an end view thereof.

The bed frame is shown with broken lines. The broken lines depict portions of the article that form no part of the claimed design.

The bed frame is shown with symbolic breaks in its width. The appearance of any portion of the article between the break lines forms no part of the claimed design.
